BENJAMIN F. FITCH, OF GREENWICH, CONNECTICUT, ASSIGNOR TO MOTOR TERMINALS COMPANY, OF WILMINGTON, DELAWARE, A CORPORATION OF DELAWARE

CONTROLLER FOR LOCKS OF DEMOUNTABLE CONTAINERS

Application filed February 11, 1931. Serial No. 515,081.

This invention relates to door locking mechanism for demountable containers, so arranged that the deposit of the container on its support may automatically lock the door or 5 leave it unlocked, according to a predetermined setting of the mechanism.

In its preferred form, my invention provides, in the base of the container, a depending mechanism which is adapted to be raised 10 to lock a door of the container, and provides, on the support on which the container is to be deposited, a shiftable abutment which the container-locking mechanism may engage or miss, according to the position of the abutment. Accordingly, when the abutment is in 15 an active position, the mere placing of a container on the support automatically locks the door of a container, while when the abutment is in an inactive position, the door locking mechanism remains idle notwithstanding the deposit of the container on that support.

I have shown, in the drawings hereof, different embodiments of my invention, and have herinafter more fully described the 20 same, and have set out the essential novel features in the claims.

In the drawings, Fig. 1 is a side elevation of a flat car equipped with my settable abutments—a container being shown in the right 25 hand portion of the figure, and indicated, but not shown, in broken lines in the left hand portion; Fig. 2 is a plan of the car and container shown in Fig. 1; Fig. 3 is a vertical section through one of the container doors, as 30 indicated by the line 3—3 of Fig. 1, but on a larger scale and showing the mechanism in locked position; Fig. 4 is an elevation of the locking mechanism itself on a still larger scale, the parts being shown in full lines in 35 unlocked position; Fig. 5 is a plan of one form of my movable abutment for controlling the locking mechanism; Fig. 6 is a vertical section through the container and the floor of the support, looking from within toward 40 the door, this view showing the door locked; Fig. 7 is a similar view of the lower portion of the container and the supporting floor, showing the door unlocked; Fig. 8 is a vertical section of the lower portion of the container and the upper portion of a supporting 45

vehicle having a modified form of adjustable abutment, the parts being shown in unlocked position; Fig. 9 is a similar view showing the parts in locked position; Figs. 10 and 11 are transverse sections on the corresponding 55 lines numbered offset planes on Figs. 8 and 9 respectively; Fig. 12 is a fragmentary side elevation of a portion of the car and container showing the operating lever for the movable abutment of Figs. 8 and 9; Fig. 13 60 is a side elevation of still another modification of the abutment; Fig. 14 is a fragmentary plan of the abutment of Fig. 13, showing the active position in full lines and the idle position in dotted lines. 65

As shown in Figs. 1, 2 and 6 to 9 inclusive, A indicates the floor of a railway car or other support, and B a demountable body adapted to be placed interchangeably on such support or on a highway truck. The truck 70 and flat car, if such is employed, each have suitable means for positioning the body thereon. Such means are now shown in Figures 1 and 2, and comprise upstanding L-shaped pieces engaging the exterior of the body at the corners, as shown in my Patent 75 No. 1,657,076, or may be upstanding conical members engaging sockets beneath the container floor as shown in my Patent No. 1,772,939. 80

The demountable body B, as shown herein, comprises a substantially rectangular container having a suitable floor frame 10, side walls 12, end walls 13 and a roof 14, and equipped with double doors 15 at the opposite sides and at opposite ends of the container. 85

Each pair of doors 15 is provided with a latching device with which the automatic lock cooperates. The latching device, the lock and the adjustable controller for the lock are shown herein particularly with reference to a pair of side doors shown in Fig. 1; but it is to be understood that a similar arrangement may be employed for each of the other pairs of doors. 95

As shown in Figs. 3 and 6, the latching device comprises a pair of upright bolts 20 and 21, slidably guided by housings 22 and 23 on the inner face of the door. The inner 100

- ends of the bolts are secured to a rocking head 25 which is rigid on a horizontal shaft 26 mounted in a door. On the outer side of the door this shaft rigidly carries a handle 27.
- 5 By oscillating the handle 27, the head 25 is rocked, which forces outwardly or draws inwardly, as the case may be, the inner ends of the two bolts 20 and 21, so that they may be projected behind transverse members of the 10 container, as for instance, behind the lintel member 18 above the door, and behind the sill member 19 below it, as shown in Fig. 3, or may be drawn respectively upwardly and downwardly to clear such members. The 15 extreme ends of the housings 22 and 23 have substantially round holes guiding the bars at these points, whereas the adjacent walls of the housings have transverse slots enabling the pairs to swing as the member 25 is rocked.
- 20 It will be seen from Figs. 3 and 6, which illustrate the same position of the latching device, that the projected bolts 20 and 21 when extended will effectively retain closed the door which carries them, and the other 25 door which is overlapped by such carrying door. I mount on the door which does not carry the shaft 26 a suitable clip 28, which the latch handle 27 is adapted to abut when the doors are latched, and then a suitable 30 sealing wire 29 may be passed through an opening in the clip and around the handle, thus sealing the container doors closed.
- After the shipper has loaded the container and closed the doors, he may latch the doors 35 and apply the seal 29 to furnish the usual protection in shipping less-than-carload freight. However, to provide an absolute lock, preventing the releasing operation of the latching bolts automatically as soon as 40 the container is deposited on its vehicle, whenever that is desired, the mechanism of this invention is provided. This will now be described, particularly with reference to Figs. 3, 4, 6 and 7.
- 45 Mounted in the floor of the container is a box-like housing 30, having in its upper wall an opening 31 through which the lower portion of the bolt 21 extends, when the bolt is in latched position. This housing 30 has a 50 pair of downwardly extending wings 32 carrying a pin 33 on which is pivotally mounted a bell crank 35. This bell crank has an upwardly extending arm 36 which is provided with an overhanging arcuate lip 55 37, which is adapted to overhang a laterally bent end 24 of the bolt 21. When the lip overhangs the bolt (as indicated in Figs. 3 and 6), it is impossible to withdraw the bolt, and accordingly, the doors are tightly locked.
- 60 When however the bell crank is in the position shown in full lines in Fig. 4, the lip entirely clears the overhanging end 24 of the bolt, and that bolt is therefore free so that the 65 handle 27 may be operated to rock the shaft 26 and thereby withdraw the two bolts 21

and 22. The bell crank is normally held in this idle position by a counterweight 39 on the end of the lateral arm 38.

When the container is suspended, or is mounted on any suitable support not equipped with a locking abutment, or if such abutment, though present, is out of registration with the bell crank, then the bell crank stands in the position shown in Figs. 4 and 7 and is thus idle. Now, on the car floor I mount suitably positioned abutments indicated at 40 in Figs. 1 to 7, at 50 in Figs. 13 and 14, and at 60 in Figs. 8 to 12. The abutment of any of these forms may be positioned to register with the bell crank or clear the same, as the case may be. These abutments are of sufficient height so that when the container is deposited on the vehicle the counterweighted end 38 of the bell crank strikes the abutment if in its active position, and is thereby swung into locked position, as shown in Fig. 6.

Now it sometimes happens that it is desired not to automatically lock the container doors when the container is deposited, but to leave one or more of such doors controlled only by its seal or padlock, so that it may be opened without removing the container from the car or support. To effect this, I provide the abutment which is on the flat car or other support in such form that it may be readily set either in an active position or idle position, according to whether the container which is to be deposited is to be automatically locked or otherwise.

One form of the abutment is illustrated in Figs. 3 to 7 inclusive, and comprises an upwardly facing stirrup 40 having its horizontal end portions 41 lying beneath overturned edges 43 of a supporting plate 44 which is shown as secured by bolts or screws 45 to the car floor A. This stirrup is shiftable manually on the supporting platform to an active or inactive position. It is adapted to be locked in either position by pins 46 passing through registering holes in the overturned flanges, the stirrup lips and plate. These pins may be provided with chains 47 held by two of the bolts 45 to prevent loss of the pins.

If we assume that Fig. 5 shows the stirrup in its active position corresponding to Fig. 6, then if the pins are taken out and the stirrup pulled forwardly, it becomes inactive, as shown in Fig. 7, and may be retained in that position by passing the pins through the other holes 48 in the retaining member.

In place of providing the retaining plate 44 on which the stirrup slides, I may simply pivot the stirrup at one end to the flat car or support, as shown in Figs. 13 and 14. In these views, the full lines show the stirrup in its active position, the stirrup, designated 50, being held by the pivot pin 51 and the removable pin 52 secured by a chain 53 to the stir-

rup itself. When this pin is removed, the stirrup may be swung into the position shown in Fig. 1 in broken lines, where it is idle, and where it may be retained by passing the pin 5 through the stirrup lip and into the hole 54.

Either form of adjustable stirrup just described has the characteristic that it is set before the container is mounted on a car and may not thereafter be changed until the container is raised. Accordingly, if it is desired at the time the container is placed on the car that it shall remain locked until it reaches destination, this form of settable abutment may be employed to advantage. 15 On the other hand, it is sometimes desired that the lock be releasable at will, being controlled either by a railroad seal or a padlock, and in that case, I prefer to employ the abutment illustrated in Figs. 8 to 12, and which I 20 will now describe.

In the figures last mentioned, the abutment 60 is in the form of a block or arm on a rock shaft 61 mounted transversely in the floor of the car and provided at its outer end with a 25 rock arm 62 which constitutes an operating handle. Now, when this handle 62 lies in a horizontal position, as shown in Fig. 12, the arm 60 (which has two surfaces at right angles to each other and at a materially different distance from the shaft axis) projects upwardly as shown in Figs. 9 and 11, and is hence in a position to engage the locking bell crank 38 and hold the container locked. The 30 operating handle may be retained in this active position by a suitable seal or padlock 64, which may be passed around the handle and through an angle clip 65 carried by the car side and forming a support for the operating handle. When the handle is sealed 35 or locked in this position, the abutment arm 60 is in position to effect the locking of the container.

When the handle 62 is turned into the upright position, as shown in broken lines at 62a in Fig. 12, the abutment arm 60 is turned down into its horizontal position as shown in Fig. 10, whereby no stop is provided for the descent of the locking bell crank 35 and this locking mechanism for the container 40 then remains inactive.

It is desirable that considerable lee-way be allowed in the height of the abutment to insure locking without requiring extreme accuracy. To this end the arm 36 of the bell 45 crank is preferably somewhat flared and the lip 37 thereon has considerable length so that it will interlock with the hook 24 in various positions of the bell crank. Fig. 6 shows the normal locked position. However, the counterweighted arm might be considerably lower than there shown, without withdrawing the hook from the lip 24, withdrawal not being complete until the counterweighted arm 39 50 has dropped nearly into the position shown 65 in full lines in Fig. 4. On the other hand, if

the abutment is of greater height than normal, it simply rocks the bell crank somewhat further and clearance in the housing is allowed to enable the bell crank to move clear up to the abnormal position indicated by the 70 uppermost broken lines.

It will be seen that the bell crank locking device is a simple construction, and self-contained in its housing, which is adapted to be readily mounted in the floor of the container 75 without causing any material obstruction to the interior; and this gravity-actuated bell crank door cooperates with any of the forms of my adjustable abutment. As soon however as the latched container is deposited on a pre-determined support having any of my abutments in active position, the automatic rocking of the bell crank locks the latch bars of the corresponding door. This insures the 80 container remaining locked until it is elevated from its support, or in case of the rock shaft embodiment, until the handle seal is broken and the handle swung to abnormal 85 position.

I claim:—

1. The combination of a container, a gravity lock therefor, a support for the container, a movable abutment carried by the support and adapted to coact with the lock and raise 90 it to active position or be out of coaction, according to the position of the abutment.

2. The combination of a container, a gravitational door locking mechanism therefor, and an adjustable controller adapted to engage and raise said mechanism to lock the door automatically upon the deposit of the container on a support or to clear said mechanism. 100

3. The combination of a container having a door in its wall, a latch for the door, a lock depending from the floor of the container for controlling the latch, and a movable abutment carried by a suitable support and adapted to be positioned on the support to miss the lock or to engage and raise it, when the container is deposited on the support. 105

4. The combination of a container having a door, a latch for the door, a lock for the latch carried in the base of the container and having a depending member, a support on which the container may be deposited and an upstanding projection movably mounted on the support in position to engage and raise the depending member or clear it as desired. 110

5. The combination with a support, an abutment movably mounted on the upper surface of the support and rising above the general level thereof, a container, door locking mechanism therefor having a raisable operating member depending from the container within the outside boundary thereof, said abutment normally standing below said member but shiftable horizontally to active or inactive position while the container is absent 120

125

130

from the support but unchangeable when the container is on the support.

6. The combination of a support, an upwardly extending stirrup movably mounted thereon, a container having a door locking mechanism with a depending operating member adapted to engage the stirrup in one position of the stirrup and clear it in another position of the stirrup.

10. A demountable container having a door, a locking device therefor including a counterweighted member tending to move to unlocked position but adapted to be moved to lock the door, and a support having an adjustably positioned abutment adapted to clear the counterweighted member or to engage it and raise it into locking position.

15. The combination of a container having a door, a downwardly extending latch bolt therefor, a counterweighted bell crank carried by the container having a lip adapted to overhang a shoulder on the bolt when the bell crank is rocked, and an adjustably positioned abutment adapted to clear or engage the bell crank when the container is deposited.

20. The combination with a support having positioning devices, of a container adapted, when lowered, to be automatically given a definite lateral position thereby, a door on the container, a locking device therefor, and means on the support independent of the positioning device for variably operating the locking device.

25. 10. A container having a door, a latching bolt for the door extending downwardly and adapted to lie behind a stationary member of the container to latch the door closed, said bolt having a shoulder, a rocking member pivotally mounted in the floor of the container and having a lip adapted to overhang the shoulder or clear it according to the angular position of the member, and a suitable support on which the container may rest, said support having an adjustable abutment adapted to occupy either of two positions, in one of which it will engage the member and rock into active position when the container is being deposited on the support, and in the other of which it will miss said member.

30. 11. The combination of a container having a door, a downwardly extending latching bolt carried by the door and having a shoulder, a housing mounted in the container floor, a bell crank on a horizontal pivot in the housing, said bell crank having an upwardly extending arm adapted to overhang the shoulder on the bolt or clear it, according to the position of the arm, said bell crank having a laterally extending arm tending to swing the bell crank into unlatched position, a support for the container having means interacting with it to position the container laterally, and a stirrup mounted on the support and arranged to be held in either of two positions

thereon to engage and operate the lateral arm of the bell crank when the container is deposited on the support or to miss said arm as desired.

35. 12. A demountable container having a door, a locking device in the floor of the container having a counter-weighted member tending to move downwardly to unlocked position, and a support having an upwardly extending abutment adapted to raise the counter-weighted member to move it into locking position when the container is lowered onto the support, said abutment being movable from active to inactive position or vice versa before the container is deposited on the support but not while it is in position thereon.

40. 13. The combination of a support, a guiding member mounted thereon, a stirrup slideable on the guiding member, a container adapted to be mounted on the support, door locking mechanism adapted to be carried by the container and engage it in one position and clear it in another of its positions.

45. 14. The combination of a support, an abutment pivotally mounted thereon, a container having a door locking mechanism with depending operating means adapted to engage the abutment in one position so as to be raised thereby and to clear it in another position.

50. 15. The combination of a support, a stirrup on the support, means for pivoting one end of the stirrup to the support, means for locking the other end of the stirrup in either of two positions leaving the stirrup active or inactive, as desired, and a container adapted to rest on the support having a door locking mechanism adapted to engage or clear the stirrup.

55. 16. A demountable container having a door equipped with a downwardly extending latch bolt, a counterweighted device in the base of the container adapted to engage an abutment when the container is lowered, there being means adapted to be moved by such engagement to interlock with the bolt, and a car carrying such abutment, said abutment being movable from active to inactive position while the container is on the support and from a position at the side of the car.

60. 17. The combination of a support provided with a horizontal rock shaft, a member on the shaft adapted to provide an active abutment in one position of the shaft and be idle in another position, and a container adapted to be deposited on the support and having a door locking mechanism adapted to engage the active abutment.

65. 18. The combination with a container having a door, a latch therefor, a locking device for the latch and a supporting vehicle having a laterally extending rock shaft, a rock arm on the inner end of the shaft adapted in

one position of the shaft to constitute an up-standing abutment to engage the door locking mechanism, and in another position of the shaft to be idle, and an operating arm on the outer end of the shaft.

- 5 19. The combination of a container having a door, locking mechanism therefor, and a movable abutment adapted to directly engage the locking mechanism or clear it according to the position of the abutment.
- 10 20. The combination of a container having a door, a bolt for locking the door, a locking member for the bolt, and a movable abutment adapted in one position to directly engage the locking member and in another position to clear it.
- 15 21. The combination of a container having a door, a downwardly extending latch bolt therefor, a pivoted member carried by the container having a lip adapted to overhang a shoulder on the bolt when the member is rocked, and an adjustably positioned abutment adapted to clear or directly engage the member when the container is deposited.
- 20 22. The combination of a container having a door, a downwardly extending latching bolt carried by the door and having a shoulder, a housing mounted in the container floor, a bell crank on a horizontal pivot in the housing, said bell crank having an upwardly extending arm adapted to overhang the shoulder on the bolt or clear it, according to the position of the arm, said bell crank having a counterweighted laterally extending arm tending to swing the bell crank into unlatched position, a support for the container having means interacting with it to position the container laterally, and movable means mounted on the support and arranged
- 25 30 35 40 45

to be held in either of two positions thereon to operate or fail to operate the bell crank as desired when the container is deposited on the support.

In testimony whereof, I hereunto affix my
45 signature.

BENJAMIN F. FITCH.
